UNITED STATES PATENT OFFICE.

WILLIAM H. MILLSPAUGH, OF SANDUSKY, OHIO, ASSIGNOR TO THE PAPER AND TILE MACHINERY COMPANY, OF SANDUSKY, OHIO, A CORPORATION OF OHIO.

CENTRIFUGAL CASTING MACHINE.

Application filed March 4, 1926. Serial No. 82,106.

This invention relates to centrifugal casting machines and particularly to the construction of dumper troughs for such machines.

5 In centrifugal casting machines the molten metal is poured into a rapidly rotating mold and the metal is thrown outwardly in the mold against the inner surface thereof by centrifugal force.

10 In one form of centrifugal casting machine, such as shown in Reissue Patent No. 15,601, the molten metal is introduced into the mold by a dumper trough having a filling opening located outside the mold and an elongated pouring slot located in the mold. The filling opening in such troughs is usually located in alignment with the center line of the pouring slot or discharge opening and unless the filling opening is closed, 15 the molten metal will spill out of the filling opening when the trough is rotated to discharge the metal into the rotating mold. This spilling of the metal is extremely dangerous as it will be thrown outwardly 20 by the rotating end plate of the machine.

This invention has for its salient object to provide a dumper trough so constructed and arranged that no metal will be spilled outside the mold during the discharge of the 25 metal into the mold.

Another object of the invention is to provide a dumper with a filling opening so arranged with reference to the discharge slot or openings that the dumper will have a maximum capacity for the molten metal.

Further objects of the invention will appear from the following specification taken in connection with the drawings, which form a part of this application, and in which 40 Fig. 1 is a longitudinal sectional elevation of a portion of a centrifugal casting machine having mounted within the mold a dumper constructed in accordance with the invention;

45 Fig. 2 is a transverse sectional elevation taken substantially on line 2-2 of Fig. 1;

Fig. 3 is a transverse sectional elevation taken substantially on line 3-3 of Fig. 1 and looking in the direction of the arrows;

50 Figs. 4, 5 and 6 are transverse sectional elevations of the dumper trough on the line 4-4 of Fig. 1, the trough being shown in three different rotative positions; and

Fig. 7 is a top plan view of a portion of

the dumper trough constructed in accordance with the invention. 55

The invention briefly described consists of a dumper trough adapted for use in a rapidly rotating mold of a centrifugal casting machine. The trough has a longitudinally extending discharge or pouring slot having a length corresponding substantially to the length of the mold. The trough also has a filling opening which in the embodiment of the invention illustrated, consists of a slot having less width than the width of the discharge or pouring slot. One edge of the filling opening is disposed in substantial alignment with the rear edge of the pouring slot, the term "rear" being used to denote the edge farthest removed from the pouring edge of the slot. The other edge of the filling opening is, however, disposed nearer the rear edge than is the pouring edge of the discharge or pouring slot. Thus what may be termed the "front" edge of the filling opening is circumferentially displaced from the front or pouring edge of the pouring slot and, therefore, the metal will be prevented from being discharged or spilled out of the filling opening as it is being poured from the dumper. Further details of the invention will appear from the following description. 70

In the embodiment of the invention illustrated there is shown a portion of a rotary mold 10 mounted for rotation in suitable bearings 11, such, for instance, as those illustrated in my Patent No. 1,058,250 and Reissue No. 15,601, or in any other suitable 80 manner. The mold shown is adapted for use in making bell end pipe and the end 12 of the mold is flared and the flared end is closed by a plate 13 and a core 14 for forming a bell end. The plate 13 and core 14 85 may be constructed, if desired in the manner described in Patent No. 1,483,372.

A dumper trough 15 is rotatably mounted in the mold 10 and one end thereof is shown at 16 as extending through the end of the 100 mold, this end being closed by a plug 17.

The dumper trough 15 has a longitudinally extending pouring slot 20 which may, if desired, be bridged at intervals by cross bars 21 for the purpose of separating the stream of molten metal to permit air to escape from the mold. The pouring slot 20 as shown is bounded by two longitudinal 105

edges 23 and 24. For the sake of convenience, the edge 23 may be termed the front edge of the pouring slot since this edge is in advance of the edge 24 in the direction 5 of rotation of the dumper trough to discharge the metal therefrom. The edge 24 may, therefore, be called the rear edge of the pouring slot.

The dumper trough 15 is also provided 10 with a filling opening 25 disposed partially beyond the end of the mold 10 and this opening is bounded by the rear edge 26 which as shown in Fig. 7, is disposed in substantial alinement with the rear edge 24 of the 15 pouring slot and by a front edge 27 which is circumferentially displaced or offset from the front edge 23 of the pouring slot. Thus, it will be seen that the wall of the dumper is continued as at 28 to prevent spilling of 20 molten metal from the filling opening as the dumper is rotated to discharge the metal through the pouring slot into the mold. In the particular form of the invention shown, the edge 27 of the filling opening is disposed substantially in alinement with the 25 center line of the pouring slot 20.

Fig. 4 illustrates the dumper in its position for filling and metal can be poured into the dumper until it reaches the dash line 30 $x-x$, thus giving a maximum capacity to the dumper. In this figure it will be noted that the portion 28 of the dumper will be disposed above a part of the metal.

In Fig. 5 the dumper has been rotated 35 to discharge part of the metal and the level of the metal left in the dumper is indicated at $y-y$.

In Fig. 6 the dumper is shown as rotated 40 still further to discharge all of the metal. From the showing in Figs. 4, 5 and 6, it will be evident that the portion 28 of the 45 dumper will form a protective wall or roof wall for preventing metal from being spilled out of the filling opening during the movement of the dumper to discharge the metal into the mold. Furthermore, it will be obvious from the showing in Fig. 4 that the part of the dumper which extends beyond the mold increases its total capacity, which is 50 important for unless the dumper capacity is large the casting walls will be thin. Furthermore, this increased capacity is at the bell end of the casting where the most metal is needed.

55 Although one specific embodiment of the invention has been particularly shown and described, it will be understood that the invention is capable of modification and that changes in the construction and in the arrangement of the various cooperating parts 60 may be made without departing from the spirit or scope of the invention, as expressed in the following claims.

What I claim is:

65 1. A dumper trough for centrifugal cast-

ing machines comprising an elongated hollow body having a longitudinally extending pouring slot therein and a filling opening adjacent one end of the body, one edge of said filling opening being displaced circumferentially from the corresponding edge of the pouring slot. 70

2. A rotatable dumper trough for use in a centrifugal casting machine having a filling slot and a pouring slot, said filling slot being 75 arranged laterally of the center line of the pouring slot and in the rear thereof in the direction of rotation of the dumper.

3. A dumper having discharge and filling 80 openings staggered with respect to an axial plane of the dumper.

4. A dumper trough for use in a centrifugal casting machine having a rotatable mold, comprising an elongated hollow body of a length greater than that of the mold, said 85 body having provided therein a delivery slot of a length substantially equal to that of the mold and a filling slot extending in prolongation of said delivery slot, but with its center line angularly displaced around said 90 body from the angle of the filling slot and substantially parallel thereto.

5. A rotatable dumper trough for centrifugal casting machines, said trough having 95 an elongated pouring slot therein and having a filling slot communicating with one end of the pouring slot, said slots having their rear edges in the direction of rotation of the trough, disposed substantially in alinement and having their front edges offset, 100 the filling slot being narrower than the pouring slot.

6. A rotatable dumper trough for centrifugal casting machines, having a pouring slot 105 extending longitudinally thereof, and a filling slot communicating with the pouring slot, one edge of the filling slot being disposed in substantial alinement with the center line of the pouring slot.

7. A rotatable dumper trough for centrifugal casting machines, having a pouring slot 110 extending longitudinally thereof, and a filling slot communicating with the pouring slot, one edge of the filling slot being disposed in substantial alinement with the center line of the pouring slot, and the other edge of the pouring slot being alined with the rear edge of the pouring slot. 115

8. A dumper trough for use in a centrifugal casting machine having a rotatable mold, comprising an elongated hollow body of a length greater than that of the mold, said body having provided therein a slot 120 extending substantially throughout the length of the mold and beyond the mold, 125 and a roof wall over that part of the slot which extends beyond the mold and partially covering said extending part of the slot.

9. A dumper trough for use in a centrif- 130

ugal casting machine having a rotatable mold, comprising an elongated hollow body of a length greater than that of the mold, said body having provided therin a slot ex-

5 tending substantially throughout the length of the mold and beyond the mold, and a roof wall over that part of the slot which extends

beyond the mold and partially covering said extending part of the slot, said roof wall being of a length sufficient to project into 10 the mold.

In witness whereof, I have hereunto set my hand this 16th day of Feb., 1926.

WILLIAM H. MILLSPAUGH.
